FILLING VALVE FOR LIGHTER TANKS
 Emil Projahn, Nurnberg, Germany, assignor to
 Gebruder Kollisch, Nurnberg, Germany
 Filed Apr. 18, 1960, Ser. No. 22,922
 Claims priority, application Germany Nov. 13, 1959
 7 Claims. (Cl. 137—19)

The present invention relates to a filling valve for the filling of permanently built-in or exchangeable tanks or reservoirs for lighters, especially of tanks or reservoirs to be filled with liquefied gas.

In connection with filling valves for lighter tanks, valves are known which in addition to the filling passage also comprise a venting passage. These known valves have either a hollow needle adapted to be inserted into the valve shank of an aerosol or filling container, or they are designed as ball valves.

Valves of this type have the drawback that they do not work satisfactorily, or cause a loss in fluid. Thus, when employing a ball valve, gas escapes into the open air taking the path of least resistance.

It is, therefore, an object of the present invention to provide a filling valve for lighter tanks or reservoirs, which will overcome the above mentioned drawbacks.

It is another object of this invention to provide a filling valve for lighter tanks or reservoirs, which will prevent the liquefied gas from escaping around the valve shank toward the outside.

It is still another object of this invention to provide a filling valve of the type set forth in the preceding paragraphs, which will permit the passage of gas but will prevent the passage of liquid, such as liquefied gas.

These and other objects and advantages of the invention will appear more clearly from the following specification in connection with the accompanying drawings, in which:

FIG. 1 is a fragmentary elevation of a filling container such as an aerosol can provided with a spray or filling nozzle having a conical tip of synthetic material.

FIG. 2 shows a gas tank or reservoir of a lighter with the filling valve in its filling position.

FIG. 3 corresponds to FIG. 2 with the exception that the valve occupies its closing position.

The filling valve according to the present invention for filling permanently built-in or exchangeable lighter tanks or reservoirs is characterized primarily by an arrangement of a semi-permeable uni-laterally osmotically acting absorber which allows the passage of gas and air but prevents the passage of liquid or liquefied gas.

Referring now to the drawings in detail, the arrangement shown in FIGS. 2 and 3 comprises a gas container or reservoir 1 having mounted thereon a valve holder 2. Movable arranged in the valve holder 2 is a valve nipple 3 which is continuously urged in upward or closing direction by means of a spring 4. The valve nipple 3 comprises a shank 5 and a conically shaped valve head 9 connected thereto or integral with said shank. The valve holder 2 is provided with an inwardly extending collar 13 having mounted thereon an absorber ring 6, the upper surface of which is engaged by the lower end of spring 4 whereas the upper end of spring 4 engages the upper end of the nipple 3. It will thus be evident that the absorber ring 6 is firmly pressed against collar 13 by spring 4. The absorber ring is porous and may consist of cardboard, sinter metal, or the like. It is necessary that the said absorber ring is permeable to air but must be able to prevent the passage of liquid therethrough.

The arrangement shown in the drawings furthermore comprises a rubber ring 7 which engages the lower surface of the collar 13 and serves as valve seat for the valve

2

head 9 when the latter occupies its closing position as shown in FIG. 3. As will be evident from FIGS. 2 and 3, the valve shank 5 is provided with a longitudinal bore 10 therethrough and with a transverse bore 11 near the lower end of bore 10. As will be seen from the drawing, the inner surface of collar 13 and of rubber seal 7 confine with the outside of the shank 5 a passage for the air and gas from the tank or reservoir.

14 is a filling or aerosol container provided with a filling or spray nozzle 8 having a tip 8a of synthetic material, as for instance rubber foam or plastic.

As will be seen from the drawing, the gas container 1 is provided with a complete filling valve. The filling process is as follows:

15 Part 8a of the nozzle 8 is pressed into the funnel-shaped part 3a of the nipple 3 of the valve. As a result thereof, valve head 9 is lifted off from the rubber seal 7, thereby freeing the transverse bore 11. The liquefied gas then passes from container 14 into the lighter container 1. The air or air-gas mixture in container 1 will then escape around valve shank 5 through absorber 6 and between nipple 3 and valve holder 2.

16 The absorber 6 according to the invention will assure that the liquefied gas cannot escape toward the outside 25 around the valve shank. While the gas under pressure is filled into the lighter tank 1, the pressure in container 1 is lower than that prevailing in the filling container or aerosol can 14. Absorber 6 has an annular shape and extends around valve shank 5. As stated above, the purpose of the absorber consists in retaining the liquefied 30 gas and to allow the air and gas particles in container 1 to escape therefrom to make room for the fresh charge of liquefied gas.

17 It is, of course, to be understood that the present invention is, by no means, limited to the particular construction shown in the drawings but also comprises any modifications within the scope of the appended claims.

What I claim is:

1. A filling valve for a tank for liquefied gas comprising: tubular holder means insertable in the upper part of the tank, a valve seat on the inner end of said holder means, a semi-permeable unilaterally osmotically acting means in the holder means between the valve seat and the atmosphere, a valve member extending reciprocably through said holder means having a valve head engageable with the tank side of said seat, a spring urging the valve member in a direction to cause the head to engage the seat and yieldable to permit movement of the valve member to separate the head from the seat, said valve member having means sealingly engaging the atmosphere side of said semi-permeable uni-laterally osmotically acting means adjacent the valve member when the valve head is moved off said seat, a filling bore extending into the valve member from the end opposite the valve head and opening laterally from the valve member adjacent the seat so as to communicate with the tank side of the seat only when the valve head is moved off said seat, and a passage leading through said valve seat and along the outside of the valve member to the tank side of said semi-permeable unilaterally osmotically acting means for the passage of gas from the tank side of the seat while preventing passage of liquid therefrom.

2. A filling valve according to claim 1 in which said valve head is conical and said valve seat is a fluid impervious resilient ring.

3. A filling valve for a tank for liquefied gas comprising: tubular holder means insertable in the upper part of the tank, a valve seat on the inner end of said holder means, a semi-permeable unilaterally osmotically acting means in the outer end of said holder means, a valve member reciprocably mounted in said holder means having a shank closely fitting said semi-permeable unilater-

ally osmotically acting means while loosely fitting said holder means and seat, a valve head on the valve member on the tank side of the seat, a spring acting on the valve member to urge the head into sealing engagement with the seat and yieldable to permit movement of the valve member to separate the valve head from the seat, a filling bore extending into the valve member from the outer end thereof and opening laterally from the shank adjacent the seat, and flange means on the outer end of the valve member for engaging the said semi-permeable unilaterally osmotically acting means when the valve member is moved inwardly to provide for the supply of liquefied gas to the tank side of the seat with the simultaneous release of gas only therefrom.

4. A filling valve according to claim 3 in which both said valve seat and said semi-permeable unilaterally osmotically acting means are located inside said tubular holder means and said tubular holder means includes an inwardly projecting annular collar between and in supporting engagement with said seat and said semi-permeable unilaterally osmotically acting means.

5. A filling valve for the filling of a lighter tank with liquefied gas, which comprises: tubular holding means insertable into a lighter tank to be filled with liquefied gas, said holding means including a valve seat at the inner end, a valve member reciprocably mounted within said holding means comprising a shank and having a valve head at the inner end on the tank side of said valve seat for cooperation therewith, said valve member having the outer end thereof provided with flange means, semi-permeable unilaterally osmotically acting means in the outer end of said holding means beneath the said flange means

5 on the valve member for permitting the passage of a gaseous medium through said semi-permeable unilaterally osmotically acting means while preventing liquefied gas from passing therethrough, spring means interposed between said unilaterally acting means and said flange means for urging said valve member in the outward direction to cause said head to engage said seat, axial passage means extending from the outer end of said valve member to a point near said valve head, and passage means near the inner end of said axial passage means and communicating with the tank side of the seat to be filled when said valve member is lifted off said valve seat and also communicating with said axial passage means, there also being passage means leading from the tank side of the seat through said seat and along the shank of the valve member to the inner side of said semi-permeable unilaterally osmotically acting means.

10 15 20 6. A filling valve according to claim 5 in which said holder means includes an inwardly projecting annular collar between the ends on the outer surface of which said semi-permeable unilaterally osmotically acting means rests while the said valve seat is disposed on the inner side of said collar.

7. A filling device according to claim 6 in which said 25 valve seat is a fluid impervious ring.
